UNITED STATES PATENT OFFICE.

SAMUEL M. KEKUEWA, OF LAHAINA, TERRITORY OF HAWAII.

HYDROCARBON-BURNER.

1,290,757.

Specification of Letters Patent.

Patented Jan. 7, 1919.

Application filed January 22, 1917, Serial No. 143,711. Renewed June 12, 1918. Serial No. 239,506.

To all whom it may concern:

Be it known that I, SAMUEL M. KEKUEWA, a citizen of the United States, residing at Lahaina, in the county of Maui, Territory 5 of Hawaii, have invented certain new and useful Improvements in Hydrocarbon-Burners; and I do hereby declare the following to be a full, clear, and exact description of the invention, such as will enable others skilled 10 in the art to which it appertains to make and use the same.

This invention relates to hydrocarbon burners and more particularly to improvements in that type of burner used for cooking 15 stoves and in which the oil feeding and vapor feeding pipes are located around the burner which forms of the pipes a gas generating apparatus.

The object of this invention is to improve 20 the construction of burners of this type by the provision of an adjustable air feeding pipe by means of which cold air drawn from the atmosphere may be fed to the burner.

25 A further object consists in the provision of an improved form of oil heating and vaporizing element.

A still further object consists in the combination with the burner of an improved 30 form of burner cap by means of which the flame is distributed to better advantage than in those burners of this type which have been heretofore known to me.

In connection with the above objects, it 35 should be stated that I have been enabled by the new improved arrangement to increase the extent or percentage of the blue flame as compared to the percentage of red flame over those burners with which I am familiar, and can secure equal results with the decreased consumption of fuel.

With the above objects in view and such others as may hereinafter appear my invention will now be fully set forth and described, reference being had to the accompanying drawings:—

In the drawings:—

Figure 1 is side elevation partly broken away of the burner,

50 Fig. 2 is a vertical section through the burner,

Fig. 3 is a plan view,

Fig. 4 is a section on line 4—4 of Fig. 1, and

55 Fig. 5 is a section on line 5—5 of Fig. 1. Referring more particularly to the draw-

ings, 1 indicates the oil pipe and standard which rises from the usual pump controlled oil tank or reservoir (not shown). The upper end of the standard 1 receives a 60 threaded base 2 from which the branch pipes 3 rise and extend diametrically upward in opposite directions and terminate in an annular vaporizing chamber 4. At equal distances from the branch pipes 3, the annular 65 chamber 4 supports the arms of the U-shaped vapor or gas tube 5 which supports, between its arms, the burner 6, the latter being adapted to project its flames centrally upward between the branch pipes 3 and the 70 arms of the vapor tube 5, so that the flame issues through the center of the annular chamber 4. Surrounding the annular chamber 4, and preferably forming an integral part of the casting is the upturned flame 75 cup 7 which incloses the heat-giving flame of the burner.

Extending downwardly through the opening in the center of the annular chamber 4 is a vertical burner tube 8 which is supported 80 against lateral movement by the annular chamber 4, and is bifurcated at its lower end, as at 9 to seat over the face of the U-shaped gas tube 5 on opposite sides of the burner 6, so that it incloses the latter. 85 The lower end of the tube 8 is open and is adapted to feed air therethrough to be mixed with the flame from the burner 6 which eventually issues through the top of the tube 8, and is deflected as will herein- 90 after appear. One of the bifurcations at the lower end of the tube 8 is extended into the right-angularly projected arm 10. Said arm 10 extends horizontally into engagement with the curved cam slot 11 of an adjusting plate 12 which is carried upon the inner end of a threaded stem 13. Said stem 13 is threaded into a plate 14 mounted upon a fixed end of the burner, in the present instance, the usual alcohol cup 15 which is 100 used to start the burner. By means of the stem 13 and the adjusting plate 12, the tube 8 may be raised and lowered by reason of the coaction of the arm 10 in the slot 11, so as to vary the degree of the opening in the bottom of the tube 8, as the latter is raised or lowered in its straddled position over the tube 5. Thus, the amount of fresh air which reaches the burner 6 can be readily regulated. Mounted upon the top of the annular 105 chamber 4 is a closely wound coil or body of wire, of copper or other suitably conductive

material which serves as a heat retaining body for the heating of the annular chamber 4, whereby the vaporizing of the fuel in the chamber 4 is maintained to the most advantageous degree. The flame which rises in the tube 8 from the burner 6 strikes against the burner cap 16 which is a cylindrical structure having its upper end closed by an arched plate or diaphragm, and has its 5 peripheral portion, adjacent the lower end provided with a number of annular rings of elongated perforations 17 through which the flames issue after they have impinged against the top of the cap 16 and turned 10 downwardly along its sides.

In operation, the above burner is started in the same manner as those burners of this type now in use, by the ignition of alcohol or other light fuel in the cup 15 after the 15 fuel in the reservoir has been pumped into the burner. As soon as the burner has been ignited, so that fuel is regularly vaporized in the chamber 4, and passing out of the burner in a flame is spread by the burner cap 20 16 as the flame turns downwardly due to its deflection by the cap 16, it heats the coil 18, and the latter becoming heated to a high degree in turn maintains the annular chamber 4 at such a temperature as will properly 25 vaporize the fuel within the chamber. The deflection of the flame by the cap 16 causes the latter to pass into the burner cup 7 through the perforations 17, the flames issuing 30 as a series of almost wholly blue jets.

When it is desired to regulate the flame, 35 the tube 8 is lowered or elevated by rotation of the stem 13, so that the arm 10 is raised or lowered by its operation in the cam slot 11. In this manner, a perfect mixture of air 40 and vapor can be accomplished, the tube 8

becoming, in fact a combination tube from which the flames are issued to the distributing element 16.

From the foregoing it will be apparent that I have provided a highly improved 45 form of burner by means of which a proper regulation of the burner flames may be secured, and which, at the same time is not complicated or difficult to manufacture.

What I claim as my invention is:—

1. A hydrocarbon burner comprising in combination, a vaporizing chamber, fuel feeding pipes and vapor pipes arranged around the vaporizing chamber, a burner disposed centrally of the fuel feeding and 55 vapor pipes, an adjustable tube surrounding the burner and rising centrally above the vaporizing chamber, means to adjust the tube vertically, a heating element supported by the chamber around the tube, and a 60 spreaded cap inclosing the heating element and the upper end of the tube.

2. A hydrocarbon burner comprising in combination, a vaporizing chamber, fuel feeding pipes and vapor pipes arranged 65 around the vaporizing chamber, a burner disposed centrally of the fuel feeding and vapor pipes, an adjustable tube surrounding the burner and rising centrally above the vaporizing chamber, a coiled metal heating 70 element supported by the chamber around the tube, and a spreaded cap inclosing the heating element and the upper end of the tube.

In testimony whereof, I affix my signature, in the presence of two witnesses.

SAMUEL M. KEKUEWA.
